US00D784395S

(12) **United States Design Patent** (10) Patent No.: **US D784,395 S**
(45) Date of Patent: **** Apr. 18, 2017**

(54) **DISPLAY SCREEN WITH GRAPHICAL USER INTERFACE**

(71) Applicant: **Under Armour, Inc.**, Baltimore, MD (US)

(72) Inventors: **Scott Laing**, Baltimore, MD (US);
Andrew Moore, Baltimore, MD (US);
Daniel Townson, Baltimore, MD (US);
Brian Carden, Baltimore, MD (US);
Marcus Piña, Baltimore, MD (US)

(73) Assignee: **Under Armour, Inc.**, Baltimore, MD (US)

(**) Term: **15 Years**

(21) Appl. No.: **29/539,261**

(22) Filed: **Sep. 11, 2015**

(51) LOC (10) Cl. **14-04**

(52) U.S. Cl. USPC **D14/487**

(58) **Field of Classification Search**

USPC D14/485-495

CPC G06F 3/0482; G06F 3/04847

See application file for complete search history.

CLAIM

The ornamental design for a display screen with graphical user interface, as shown and described.

DESCRIPTION

The FIGURE is a front view of a display screen with graphical user interface showing my new design.

The broken lines shown in the FIGURE illustrate portions of the display screen with graphical user interface that form no part of the claimed design.

1 Claim, 1 Drawing Sheet
